UNITED STATES PATENT OFFICE

171,457

ELECTRIC LANTERN

Ralph T. Osman, Whitefish Bay, Wis.

Application March 4, 1953, Serial No. 23,881

Term of patent 14 years

(Cl. D48—24)

To all whom it may concern:

Be it known that I, Ralph T. Osman, a citizen of the United States of America, residing at the village of Whitefish Bay, county of Milwaukee, State of Wisconsin, have invented a new, original, and ornamental Design for an Electric Lantern, of which the following is a specification, reference being had to the accompanying drawings, forming a part hereof.

In the drawings:

Fig. 1 is a front perspective view of an electric lantern showing my new design;

Fig. 2 is a rear elevational view thereof;

Fig. 3 is a side elevational view; and

Fig. 4 is a top plan view.

I claim:

The ornamental design for an electric lantern, as shown.

RALPH T. OSMAN.
